INVENTOR:
Eugene King Willard
BY Harry T. Williams

ATTORNEY

UNITED STATES PATENT OFFICE.

EUGENE KING WILLARD, OF BOSTON, MASSACHUSETTS.

AUTOMOBILE BODY ADVERTISING PANEL.

Application filed March 17, 1923. Serial No. 625,907.

To all whom it may concern:

Be it known that I, EUGENE KING WILLARD, a citizen of the United States, residing at Boston, in the county of Suffolk 5 and State of Massachusetts, have invented certain new and useful Improvements in Automobile Body Advertising Panels, of which the following is a specification.

The invention to be hereinafter described 10 relates to advertising panels, and more particularly to an advertising panel for a vehicle body, such, for example, as disclosed by my copending application Serial No. 616,607, filed February 2, 1923.

One of the purposes of the invention is 15 to provide a window with a translucent screen having pictorial or other matter thereon, and an illuminating box mounted at the back of the screen and provided with 20 electric lamps for throwing their light through the screen to illuminate the matter thereon. The back of the box may have a reflecting surface for reflecting and diffusing the light from the lamps through the 25 screen.

The light has greatest intensity at the 30 spots where the lamps are located. Another purpose of the invention, therefore, is to provide means for shielding the lamps at their sides facing the screen, so that the 35 light will not be directly thrown from the lamps to the screen, and therefore, spots of light at the locations of the lamps will not be visible externally of the screen.

It is desirable from time to time to introduce 40 different screens in the window frame, in order that the pictorial or other matter displayed may be varied in accordance with requirements of different advertising. An-

other purpose of the invention, therefore, 45 is to provide means for detachably securing the screen frames in the window frame, and means for securing the reflecting box to the window frame having provision permitting 50 movement of the box away from the window frame to enable ready access to the screen frame for the purpose of quickly removing the same from the window frame and substitution of another screen frame therefor.

With the aforesaid and other purposes in view, the character of the invention will be best understood by reference to the following description of one good form thereof shown in the accompanying drawing, wherein:

Fig. 1 is a perspective view of an advertising panel embodying the invention, a portion of the reflecting box being broken away to disclose parts in and beyond the 60 same;

Fig. 2 is a vertical section through the panel showing the reflecting box detached from the window frame; and

Fig. 3 on an enlarged scale is a sectional 65 detail to be referred to.

Referring to the drawing, the advertising panel shown therein as one good form of the invention, comprises a window frame 1 which may be mounted in the side 3 of a 70 vehicle body, such, for example, as that disclosed in my application above referred to. The window frame may have a rabbet 5 formed therein to receive a glass pane 7 for protecting the screen to be described. 75 The edges of the pane may rest on cushion strips 9 of rubber or other suitable material mounted in the rabbet. The glass pane and the cushion strips may be secured in place by cleats 10 mounted in the rabbet 80 and secured to the window frame by screws 10.

The screen, in the present instance of the 85 invention, comprises a sheet of canvas 11 or other suitable translucent material which 90 may have pictorial or other advertising matter painted or otherwise produced thereon. This canvas sheet has its margins bent over and tacked or otherwise secured to a frame 13 which may have beveled faces 15 facing the 95 canvas and spaced therefrom to admit light to the margins of the canvas. To removably secure the screen frame in the window frame, buttons 17 may be secured to the cleats 10, and may be adjusted to secure 95 or release the screen frame as desired.

The means for illuminating the screen in order that the pictorial or other matter thereon may be conspicuously visible when viewed from the exterior of the vehicle body, 100 in the present instance, comprises an illuminating box or casing 19 having sides 21 and a back 22, said box being of appropriate size to fit in the window frame 1 back of the screen. The inner faces of the sides and 105 the back of the box may be painted white or otherwise treated to reflect light.

Suitable illuminating means may be mounted in the box, in the present instance, 110 in the form of incandescent lamps 23 mounted at intervals on the sides 21 of the box and connected to conductors 25 which project

through an eye 27 in the back of the box, said conductors receiving electrical current from any suitable source.

To prevent spots of light at the locations 5 of the lamps from being visible through the translucent screen, the lamp bulbs may have their sides 29 facing the screen painted black or otherwise rendered opaque. The construction is such that the light will not 10 be directly thrown from the electric lamps through the screen, but will be thrown from the lamps onto the back of the box and be reflected thereby through the screen. As a consequence, the light will be desirably diffused so as uniformly to illuminate the 15 screen throughout the area thereof.

The box may be detachably secured to the window frame by buttons 31 secured to the window frame and adapted to over- 20 lap the margins of the back of the box. These buttons may be easily adjusted to release the box or to lock the same in position.

When it is desired to remove a screen from 25 the window frame and to substitute another therefor, it is merely necessary to release the buttons 31 from the box, thereby allowing the same together with the lamps carried thereby to be removed from the window 30 frame. This will expose the screen and the securing buttons 17 for convenient access. On release of the buttons 17 from the screen frame, the screen may be quickly and easily removed from the window frame 35 and another screen substituted therefor. Then the buttons 17 may be adjusted to

locking position, the box may be returned to the window frame, and the buttons 31 may be returned to locking position.

By my invention, a simple, commercially 40 practicable advertising panel is provided, enabling efficient illumination of the pictorial or other matter on the screen, so as to render the same conspicuously visible, and different screens may be readily introduced into the window frame without substantial loss of time.

It will be understood that the invention is not limited to the specific embodiment shown, and that various deviations may be 50 made therefrom without departing from the spirit and scope of the appended claim.

I claim—

An advertising panel for a vehicle body comprising a window frame having a glass pane therein, a translucent screen having pictorial or other matter thereon, a frame for said screen removably mounted in the window frame back of the glass pane, an illuminating box mounted in the window 55 frame back of the screen, electric lamps mounted at intervals at the sides of the box and having opaque surfaces facing the screen, said box having a reflecting surface at the back thereof for reflecting the light from the lamps through the screen, and means for securing the box to the window frame having provision permitting movement of the box to allow removal of the screen from the window frame and substitution of another screen therefor.

EUGENE KING WILLARD.
